UNITED STATES PATENT OFFICE

HARRY HERTZBERG, OF BROOKLYN, NEW YORK

PULSATING IRRIGATOR

Application filed May 14, 1927. Serial No. 191,340.

This invention relates to hydraulic irrigating apparatus for use in irrigating the intestinal canals.

An object of the invention is to provide such a device with a pulsating delivery which will have a massaging effect upon the walls of the intestines and which, by intermittently expanding the intestines, will break loose any concretions that may be adhering thereto. This hydraulic vibratory massage has a stimulating and beneficial influence on the intestinal tissues and breaks up and washes away adhering toxic matter that could not otherwise be removed.

15 A further object is the provision of means for varying the force and frequency of the pulsations to adapt the treatment to the condition and needs of the patient.

The apparatus is particularly useful for 20 administering high enemas, since the alternating stretching and relaxing of the bowel walls assist in inserting the head of the irrigator into the upper intestine.

While preferred forms of the invention 25 have been disclosed for purposes of illustration, it should be understood that changes may be made in the structure without departing from the spirit and scope of the invention as hereinafter set forth and claimed.

30 In the drawings:

Fig. 1 is an elevation of one embodiment of the invention.

Fig. 2 is a section through the interrupter valve of Fig. 1.

35 Fig. 3 is an enlarged elevation of the nozzle used in Fig. 1.

Fig. 4 is an elevation partly in section of a modified form of the invention.

Fig. 5 is a view similar to Fig. 4 showing 40 a further modification.

Referring to the drawings more specifically, reference numeral 10 indicates a water reservoir of any suitable material, such as glass, and situated at about six or eight feet 45 above the floor to produce a proper pressure at the nozzle. Numeral 11 refers to the double nozzle, which is shown on an enlarged scale in Fig. 3. This nozzle comprises an outer tube 12 having one end tapered and 50 closed as at 13, while the opposite end is open

as at 14. A delivery tube 15 passes through the side of the tube 12 above its open end, extends along the axis of tube 12, and is joined to the inner wall of tapered end 13 at 16. The end 13 is pierced with apertures 55 17 communicating with the interior of tube 15 to permit flow of water from the nozzle, which apertures 18 formed lower down in the tip 13 permits escape of waste matter through the outer tube 12.

A rubber tube 19 forms a feed line connecting the reservoir 10 with nozzle 11, the interrupter valve 20 being interposed in the feed line. This interrupter valve comprises a rotary plug 21 having a passage 22 extending thereacross, and connected to the drive motor 23.

When this irrigator is in use the motor revolves the interrupter valve, thereby periodically interrupting flow through feed line 70 19 and causing a pulsating discharge from the delivery nozzle. The speed of the motor can be suitably controlled to govern the duration of the pulsations.

In the species shown in Fig. 4 the force of 75 the discharge is derived from a power pump instead of from gravity feed. This species is illustrated as having a single nozzle 24, although obviously it may have a double nozzle as in Fig. 1 if desired. The feed line 25 extends from the nozzle to the reservoir 26, and the force pump 27 is interposed in the feed line. The pump 27 is a single acting plunger pump with check valves 28 arranged so that the pump draws liquid from the reservoir and 80 forces it toward the nozzle. The crank arm 29 of the pump is operated by a gear wheel 30 which carries a plurality of crank pin holes 31 distributed along its radius to provide means for varying the length of the stroke of 85 the pump. Wheel 30 is moved by a motor 32 through worm 33, and the variable resistance 34 provides means for varying both the frequency and intensity of the pulsations delivered by the nozzle.

In the species of Fig. 5 the pump 35 is driven by a motor 36 through reduction gears 37 and 38. The valve arrangement is similar to that of Fig. 4 but a by-pass 39 leads from the delivery chamber 41. A screw valve 42 100

controls the amount of liquid delivered through the by-pass. This apparatus is provided with a double nozzle similar to that shown in Fig. 1. In this device the screw 42 **5** may be adjusted while the pulsator is working to regulate the pressure and volume of water delivered by the nozzle.

I claim:

1. An intestinal irrigator comprising a **10** nozzle adapted for insertion into the intestines, a source of liquid supply, a feed line connecting the nozzle to the source of supply, a reciprocating pump in said feed line to cause a pulsating delivery from the nozzle, and **15** means for regulating the stroke of the pump to vary the amount of water delivered at each pulsation.
2. An intestinal irrigator comprising a **20** nozzle adapted for insertion into the intestines, a source of liquid supply, a feed line connecting the nozzle to the source of supply, a reciprocating pump in said feed line to cause a pulsating delivery from the nozzle, and means for regulating the speed of the pump **25** to vary the rate of pulsation.
3. An intestinal irrigator comprising a **30** nozzle adapted for insertion into the intestines, a source of liquid supply, a feed line connecting the nozzle to the source of supply, a reciprocating pump in said feed line to cause **35** a pulsating delivery from the nozzle, said pump being provided with a by-pass connecting its delivery chamber to its inlet, and adjustable means to regulate the amount of flow through the by-pass to thereby vary the volume of liquid and the force of each pulsation.
4. An intestinal irrigator comprising a **40** nozzle adapted for insertion into the intestines, a source of liquid supply, a feed line connecting the nozzle to the source of supply, a reciprocating pump in said feed line to cause a pulsating delivery from the nozzle, means for driving the pump at a uniform speed, a by-pass for relieving part of the pressure in **45** the delivery chamber of the pump, and means operable while the pump is working to regulate the flow through the by-pass to thereby vary the volume of liquid and the force of each pulsation.
5. An intestinal irrigator comprising a nozzle, adapted for insertion into the intestines, **50** a source of liquid supply, a feed line connecting the nozzle to the source of supply, and a motor driven reciprocating pump in said feed line, said pump being adapted to cause a pulsating delivery from the discharge nozzle.

In testimony whereof I affix my signature.
HARRY HERTZBERG.
